UNITED STATES PATENT OFFICE.

MARIUS GROIGNARD, OF MARSEILLES, FRANCE.

VALVE.

SPECIFICATION forming part of Letters Patent No. 605,711, dated June 14, 1898.

Application filed April 17, 1896. Renewed January 13, 1898. Serial No. 666,578. (No model.)

To all whom it may concern:

Be it known that I, MARIUS GROIGNARD, a citizen of the French Republic, residing at Marseilles, France, have invented certain new and useful Improvements in Valves; and I do hereby declare the following to be a full, clear, and exact description of the invention, such as will enable others skilled in the art to which it appertains to make and use the same.

The present invention relates to a valve for steam or other fluid under pressure adapted to close rapidly and automatically in case of rupture of the conduit and adapted to retain the normal open position by the pressure of the fluid when once the valve has been removed from its seat.

Figure 1 of the accompanying drawings is a vertical cross-section through my improved valve in normal closed position. Fig. 2 is a vertical cross-section showing the parts of the valve in open position. Fig. 3 is a vertical cross-section through the valve, showing the parts in the position when in case of accident the valve is closed automatically.

The flanged opening to be connected to the conduit or pipe coming from the boiler or other source furnishing fluid under pressure is designated by the letter A, and B on the opposite side is the exit of the steam or other fluid.

C is a valve-plate forced from below against its seat.

P is a hollow piston movable in an open cylinder P', forming part of the body P², which is screwed into the inner partition B' of the valve-casing, as shown, and the lower edge of which is smoothed, so as to form a seat for the valve-plate C. The piston P is connected with a smaller piston p by means of a rod Q, on which the valve-plate C is screwed or otherwise secured. The small piston p acts in a cylinder p', having openings p² at or near the lower edge. The ordinary hand-wheel of the valve operates in the well-known manner a screw-spindle D, which is provided at its lower end with a head D', screwed upon or

otherwise secured, which works in the hollow space of the piston P.

The operation of the described valve is the following: By turning the hand-wheel the spindle D is moved down until it strikes the bottom plate of the piston P, forcing the same down simultaneously with the piston p and the valve-plate C, so that the steam or other fluid can pass from A to B, as shown by the arrows. Then the hand-wheel is turned backward until the head D' of the spindle is about half-way up in the hollow piston P. This constitutes the normal open position, as shown in Fig. 2. The pressure of the fluid will prevail in all parts of the valve, and as the surface of the piston P is greater than the surface of the piston p the pressure will keep the parts in the open position, Fig. 2. If breakage occurs in the conduit branching off from the opening B, the pressure under the partition B' will be higher than the pressure above the same, and acting on the lower surface of the piston p it will start to lift the same, with the rod Q and the valve-plate C, so that the latter moves against its seat and intercepts the flow of the fluid. The parts will then take the position shown in Fig. 3.

Having thus described my invention, what I claim as new, and desire to secure by Letters Patent, is—

In a valve having an open cylinder P' and a body P² integral therewith, a hollow piston P working in said cylinder, a rod Q secured to said hollow piston, a piston p secured to opposite end of said rod, a cylinder p' having openings p² and adapted to inclose said piston p and a valve-plate suitably mounted on said rod, all of said parts being combined and for the purposes substantially as described and set forth.

In testimony whereof I affix my signature in presence of two witnesses.

MARIUS GROIGNARD.

Witnesses:

M. GAN,

A. SEMERCIE.
